UNITED STATES PATENT OFFICE

ADOLPH POTDEVIN, OF GARDEN CITY, NEW YORK, ASSIGNOR TO POTDEVIN MACHINE COMPANY, OF BROOKLYN, NEW YORK, A CORPORATION OF NEW YORK

MACHINE FOR HANDLING STRIP MATERIAL

Application filed August 19, 1930. Serial No. 476,373.

The present invention is directed to an improved apparatus for use in connection with the simultaneous handling of a plurality of sheets of material, particularly in connection with bag making machines in the making of multi-walled bags. Heretofore in machines of this character it has been necessary to stop the machine when a paper supply roll is exhausted in order that a new roll of paper may be substituted. This not only consumes time but is objectionable in that where a machine handling a plurality of webs at a time is shut down it is difficult to start the machine in operation again with the webs properly registered with each other.

The present invention, therefore, has for another one of its objects the provision of means whereby not only may the new roll of paper or other material be placed in the machine without shutting the machine down but this roll may be accurately positioned in the machine with the minimum of effort so as properly to register the material with the other webs or sheets already in the machine and to maintain the necessary tension on the web.

In the drawings accompanying this application:

Fig. 1 is a view in elevation of an embodiment of my invention;

Fig. 2 is a plan view of a detail;

Fig. 3 is a section on the line 3—3 of Fig. 1;

Fig. 4 is an elevational view showing a new roll being placed in the machine; and

Fig. 5 is a plan view of one of the rolls of paper or other material being handled and the various mechanisms for properly positioning the same in the machine.

Referring to the drawings in detail: As above pointed out this invention relates to a machine for handling simultaneously a plurality of strips or webs of paper such, for example, as a bag making machine for the making of multi-walled bags. For purposes of illustration I have shown a machine for handling three webs of paper simultaneously. It is to be understood, however, that the number may be varied as desired.

1, 2 and 3 designate, respectively, three

stands for the paper supply rolls, two rolls of which I will designate 4 and 5, respectively, each roll as will be understood from an inspection of the drawings resting in open bearings designated 7 and 8, respectively, at 55 the top of the stands 1 and 2.

Each stand is provided with brackets 10, and mounted in each of these brackets and extending transversely of the machine, i. e., lengthwise of the rolls of paper is a hollow 60 rod 11. Extending through each of these rods and projecting from each end thereof is a rod 12 having an arm 13 affixed to each end. The arms on one stand extend toward the roll of paper on the adjacent stand so that 65 the outer end of these arms overlie the paper roll as will be seen from Fig. 1.

The outer ends of each pair of brake arms 13 are connected to each other by a rod 14 which also extends lengthwise of the paper 70 rolls. Intermediate the arms 13 and about midway of the rod 14 is a friction device or brake, which as a whole is designated 15. This brake comprises two spaced mounts 16 carried by rod 14 and in turn carrying short 75 rods 17 over which and the rod 14 is mounted a piece of leather belting or other suitable material 18. The rod 14 and rods 17 are arranged roughly in the form of a triangle with the rod 14 at the apex so that one lead of the 80 leather belting or other material 18 will rest upon the paper roll.

On each of the rods 14 and intermediate the arms 13 and the friction device 15, I provide plates 19, one at each end of the 85 paper roll. These plates are clamped to the rod 14 by a bolt 20 and are so spaced apart as to lie against the ends of the roll of paper.

Each roll of paper is mounted, as above noted, in an open bearing so as to be lifted 90 out or lowered into the bearing with the minimum of effort, and in this connection it is to be noted that each roll is supported in its bearings by a shaft 21. Each of these shafts is provided with cone shaped members 23 95 adapted to be driven or wedged into the end of the paper roll and locked to the shaft by screws 22.

The end of one of each pair of arms 13 adjacent each stand is provided with an annular

flange 24 which rides in a notch 25 cut in a nut 26 mounted on a threaded rod 27 which is mounted for rotation but held against longitudinal movement in the bracket 10. 5 The rod 27 is provided with a handle 28 and rotation of this handle will of course effect movement of the nut 26 and hence longitudinal movement of the shaft or rod 12 and a lateral movement of each pair of arms 13, 10 it being understood of course that this same mechanism is provided at each stand.

Inasmuch as the arms 13 carry the rods 14 and the latter carry the plates 19 it will be obvious that lateral movement of the arms 15 13 will effect lateral movement of the plates 19 and hence longitudinal movement of the paper roll in its bearings. This construction, therefore, permits of longitudinal adjustment of the paper rolls, i. e., lateral adjustment 20 of the paper webs so that the paper webs may be properly registered with each other at all times. This permits the roll of paper to be accurately positioned in the machine initially.

25 In order that the pressure of the friction devices 15 on the paper rolls may not be applied before the new roll has been started, splice made and the roll brought up to speed, I pivotally mount an arm 29 on each stand, 30 each arm being notched as shown at 30 and adapted to support the arms 13 in any predetermined position desired with respect to the paper roll, the idea being that initially when the paper rolls are of maximum diameter and before the roll is started and splice made, as above referred to, the arms 13 will be supported adjacent the tops of the arms 29 to prevent friction device 15 from coming 35 in contact with the roll before it has been 40 properly spliced, but permitting the guide plates 19 to engage the ends of the roll for alignment. Eventually the arms 29 will be removed entirely as shown at the center roll in Fig. 1.

45 I have previously explained that the present invention provides means for permitting of the removal of an empty or substantially empty roll from the machine and its substitution by a full roll. In this connection I 50 mount a pair of arms 31 provided with counterweights 32 on the hollow shaft 11 on each stand. Each one of the shafts 11 is also provided with a worm gear 33 adapted to be rotated by a worm 34 driven from a crank 55 35 through bevel gears 36 and 37. The outer or free ends of each of the arms 31 is provided with an open bearing 38. Each one of these bearings has a spring loaded block 39 which engages shaft 21 and prevents the same from 60 rolling out of the bearing when the arms 31 are in a vertical position during the loading operation.

65 The lifting arms 31 are of such length that rotation of one of the cranks 35 will bring the bearings of the corresponding arms into en-

gagement with the shaft 21. The shaft 21 is provided with a pair of spaced collars 42 and the bearings 38 of the lifting arms 31 engage the shaft 21 between these collars and to keep the proper alignment of the nearly spent roll while being lifted from its main bearings to make room for a new roll, I provide a pin 40 which is slidably mounted in the end of the arm 31 and clamped in position by thumb screw 41. 70 75

The stand 3 is provided with two pairs of brackets 10 and 10^a as distinguished from the single pair of brackets of the other stands. This is for the purpose of permitting two friction devices 15 to be pivoted on this stand, one friction device of course being for the next succeeding roll of paper as above explained, while the other is for the roll carried in the stand 3. 80

In the drawings in Fig. 4, I have shown a fresh roll of paper 50 being lowered into place on the stand 3, Fig. 1 showing the roll in position on the stand.

In practice and with the machine in operation the arms 31 at the stand 3 and which initially stood in the position of the arms 31 at the stand 2 in Fig. 1 are moved or swung upwardly by rotating the crank 35. This brings the bearings 38 carried at the outer end of these arms under the paper roll shaft 21 and continued rotation of the crank 35 will lift the nearly empty roll 51 out of its bearings in the stand 3 and raise it to the position shown in Fig. 1 and in Fig. 4. 90 95

The nearly spent roll 51 is moved by the arms 31 to a position far enough to the left to permit of the lowering of the new roll 50 without the same coming in contact with the moving web of paper from the roll 51. After placing the new roll 50 in position, the leading edge of this roll being supplied with an adhesive 53 and with this leading edge maintained in the upper part of the roll as shown in Fig. 4 and the lifting tackle employed in lowering the roll 50 into position removed, the arms 13 cooperating with the roll of paper in the particular stand under consideration are lowered to a position to bring the registering plates 19 into engagement with the new roll to properly register the same. At the same time the arm 29 with its notches 30 is moved to such position that the proper notch therein will be engaged by the pin 13^a to keep the friction device 15 with its friction belt out of engagement with the new roll. 100 105 110 115 120

When it is desired to start the new roll the same is given a start manually in the direction in which the web unreels and the glued surface 53 inserted between the material 52 coming from the roll 51 and the idler roll I, 125 to splice the old roll and the new roll to each other and without stopping the machine.

After the old roll 51 is spent the shaft 21 is removed from the arms 31, then by again operating the handle 35 the arms 31 are 130

moved in a counter-clockwise direction into position below the new roll shaft as shown at stand 2 in Fig. 1 so as to be ready to pick up the roll 50 when the latter has been sufficiently exhausted of its supply of paper to require removal from its bearings and insertion of another new roll in place thereof.

It is to be understood that changes may be made in the details of construction above described within the purview of this invention.

What I claim is:—

1. In a machine for handling strip material, the combination of a support or stand for a roll of the material, a pair of arms pivoted on said stand or support, bearings carried by said arms, and worm and gear mechanism for rotating said arms to bring said bearings beneath the supply roll, continued rotation of said arms lifting the roll out of its original position into a new position for rotation, while continuing the operation of withdrawing material from the roll.

2. In a machine for the simultaneous handling of a plurality of strips of material, the combination of a plurality of stands or supports for the supply rolls, and brake mechanism carried by each support for braking the supply roll carried on the next succeeding stand or support.

3. In a machine for the simultaneous handling of a plurality of strips of material, the combination of a plurality of stands or supports for the supply rolls, braking mechanism carried by each stand or support, the braking mechanism carried by one stand braking the supply roll on the succeeding stand, and brake regulating means carried by each stand for regulating the brake for the roll on the stand carrying the regulating means.

4. In a machine for the simultaneous handling of a plurality of strips of material, the combination of a stand or support for each supply roll of material, brake mechanism comprising a pair of pivoted arms mounted on each stand, a flexible braking member carried by each pair of arms, the braking member carried by the arms on one stand engaging the supply roll mounted on the succeeding stand, and a pivoted arm mounted on each stand and cooperating with said brake carrying arms to regulate the brake pressure on each supply roll independently.

5. In a machine for handling strip material, the combination of a support or stand for mounting the material supply roll for rotation, a shaft attached to the supply roll and directly supporting the same in its stand, spaced flanges adjacent one end of said shaft, a pair of pivoted arms, each of which is provided with a bearing for the said shaft, and means for rotating said arms as a unit to bring the bearings thereof beneath said shaft, continued rotation of said arms raising the

roll out of its bearings in said stand, the bearing carried by one of said arms engaging the shaft between the flanges thereon to restrict end movement of the roll with respect to said arms.

6. In a machine for handling strip material, the combination of a stand or support for rotatably mounting the supply roll of material, a pair of arms adjacent the supply roll and provided with adjustable bearings adapted to receive the supply roll, and means for rotating said arms to raise the supply roll out of its bearings in said stand, continued rotation of the arms carrying the roll into a new position for rotation, without interrupting the operation of withdrawing material from the roll.

7. In a machine for handling a web of material, the combination of a stand or support comprising bearings in which the supply roll of material is rotatably mounted, rotatable means for removing the supply roll from the bearings of said stand; continued rotation of the said rotatable means supporting the supply roll for rotation in another position, and a guide roll about which the material from said supply roll and the material from a replenishing roll placed in said bearings are led to effect the splicing of the two materials to each other.

8. In a machine for handling a web material, the combination of a stand for a supply roll of said material, said stand comprising bearings in which the roll is rotatable, and means rotatable into position during the operation of withdrawing material from the supply roll to remove the roll from its bearings in said stand and support the roll for rotation in another position, continued forward rotation of said rotatable means effecting a positioning of the said rotatable means into position to remove the next supply roll from said bearings.

9. In a machine for handling a web of material, the combination of a stand or support comprising bearings for rotatably mounting a supply roll of material, means rotatable into position during the operation of withdrawing material from said supply roll to remove the supply roll from said bearings and to support the roll for rotation in another position, means for joining or splicing the material of said supply roll to the material of a second supply roll placed in said bearings, during the withdrawing of material from both rolls, and means for continuing the forward rotation of said rotatable means to move the same into position to remove said next supply roll from its bearings.

10. In a machine for the handling of strip material, the combination of a stand or support for a supply roll of material, a pair of pivoted arms adjacent said stand, bearings for the supply roll carried by said arms, and

means for rotating said arms to bring said bearings into position to engage said supply roll, continued rotation of said arms lifting the roll from its support and supporting the 5 roller for rotation in another position while continuing the operation of withdrawing material from the roll, continued forward rotation of said arms bringing the same into position to remove the next succeeding 10 supply roll from said stand.

11. In a machine for handling strip material, the combination of a support for a supply roll of material, a pair of arms adjacent said support, means for rotating said 15 arms to raise the supply roll away from said support, continued rotation of the arms while continuing the withdrawing of material from the supply roll carrying the supply roll out of the path of a new supply roll of material 20 being placed in said support.

12. In a machine for handling strip material, the combination of a support for a supply roll of said material, a pair of pivoted counterweighted bearing arms mounted adjacent the supply roll, and a worm and gear mechanism for rotating said arms, continued rotation of said arms bringing the bearings thereof into engagement with the supply roll to raise the supply roll out of said support, 25 while the operation of withdrawing material from the supply roll continues, further forward rotation of the said arms moving the same into position to lift the next succeeding supply roll from said support.

35 This specification signed this 12th day of Aug., 1930.

ADOLPH POTDEVIN.
